UNITED STATES PATENT OFFICE.

CHARLES VAN CISE WHEELER AND ALEXANDER GEORGE MCKENNA, OF
PITTSBURG, PENNSYLVANIA.

PROJECTILE.

No. 841,753:

Specification of Letters Patent.

Patented Jan. 22, 1907.

Application filed July 26, 1906. Serial No. 327,796.

To all whom it may concern:

Be it known that we, CHARLES VAN CISE WHEELER and ALEXANDER GEORGE MCKENNA, citizens of the United States, and residents of Pittsburg, county of Allegheny, and State of Pennsylvania, have invented certain new and useful Improvements in Projectiles, of which the following is a specification.

Our invention relates to capped projectiles. Its object is to increase the penetration of such projectiles without interfering with their flight.

For the purpose of illustrating our invention we have shown it as applied to a shell adapted to carry an explosive charge; but it is obvious that this is non-essential to the invention, which is not limited thereto.

In the drawing, 1 designates the body of a shell, having a point 2, the tip of which is indicated at 3. The shell is provided with the usual chamber 4, rear closure 5, and rifling-band 6. Covering the forward end of the point of the shell is a cap 7, which in the present instance is shown as secured thereto by rods 8, engaging in coöperating annular grooves 9 and 10, formed in the point of the shell and in the inner wall of the cap, respectively. This method of fastening the shell is described and claimed in our Patent No. 748,827, dated January 5, 1904, and of course forms no part of the present invention. The body of the shell is usually formed of hardened steel and the cap 7 of a soft steel. The present invention consists in placing between the outer cap 7 and the point of the shell an inner cohesive cap 11, made of a relatively soft metal, preferably soft lead. It will be seen that this cap extends over the tip 3 of the shell and is of substantial thickness, having its greatest thickness approximately at the extreme tip of the shell and extending rearwardly therefrom for a short distance. As shown, the outer cap 7 extends rearwardly over the point of the shell to a greater distance than the inner cap 11, so as to hold the inner cap in position and so as to permit the securing of the outer cap directly to the shell. As a convenient means of securing the inner cap 11 within the outer cap during the assembling of the projectile we preferably form in the latter an annular groove 12 into which a corresponding annu-

lar projection 13 in the inner soft-metal cap is forced.

We are aware that heretofore soft-steel caps have been secured to the points of shells by means of solder. Our present invention is clearly distinguished from this former construction in that the cap 11 in this case has a wall of substantial thickness, and particularly in that it may be applied to the shell without heating its point, which of course tends to draw the temper and is therefore deleterious.

The advantage of the inner cohesive lead or soft-metal cap is that it is more inert than the steel cap and does not tend to fly away from the point of the shell during impact against the armor-plate, thereby forming a very perfect lubricant for the point. The heat developed in impact undoubtedly acts to melt this lead cap, and thereby cover the point for a considerable distance, thus increasing its penetration. The lead being in a state of complete compression between the outer cap and the point of the shell is fully as effective as the steel cap itself for the purpose of delivering the blow of the shell through the outer cap to the plate.

The use of soft metal, such as lead, contrasts with graphite as a lubricant because of the cohesive qualities of the lead, even when undergoing deformation, and the capacity of the lead to melt under excessive heat and pressure, neither of which qualities have any analogy in graphite so far as we are aware.

By the term "metal" as used in the claims referring to the inner cap we of course include any alloy of two or more soft metals, although we believe soft lead to be at least as advantageous as any other metal or alloy that can be used for this purpose.

What we claim is—

1. A capped projectile having an inner cap of relatively soft metal interposed between the tip of the shell and the outer cap, the wall of said inner cap being of substantial thickness.

2. A pointed projectile comprising a body, an inner cap of relatively soft metal, the walls of which are of substantial thickness, and an outer cap covering said inner cap and secured to the point of the body.

3. A pointed projectile comprising a hardened-steel body, an outer cap of soft steel, and an inner cap of relatively soft metal in-

terposed between the tip of the body and the inner wall of the outer cap.

4. A pointed projectile comprising a hardened-steel body, an outer cap of soft metal, and an inner cap of metal not harder than lead interposed between the tip of the body and the inner wall of the cap.

5. A pointed projectile comprising a hardened-steel body, an outer cap of soft metal, and an inner cap of soft lead interposed between the tip of the body and the inner wall of the outer cap.

6. A capped projectile having an inner cap of relatively soft metal interposed between the tip of the shell and the outer cap, the maximum thickness of said inner cap being approximately at the extreme tip of the body.

7. A pointed projectile comprising a body, an inner cap of relatively soft metal, and an outer cap covering said inner cap and secured to the point of the body, said outer cap extending rearwardly a substantially greater distance than said inner cap.

8. A pointed projectile comprising a body, an inner cap of relatively soft metal, an outer cap covering said inner cap and secured to the point of the body, said outer cap extending rearwardly a substantially greater distance than said inner cap, and means for securing said outer cap on said body located rearwardly of said inner cap.

9. A pointed projectile comprising a body,

an inner cap of relatively soft metal, an outer cap covering said inner cap and secured to the point of the body, said outer cap extending rearwardly a substantially greater distance than said inner cap, and means including coöperating grooves on said outer cap and said body and a rod filling said grooves for securing said outer cap on said body, said means being located rearwardly of said inner cap.

10. A pointed projectile having a cap provided with a relatively soft - metal lining within the cap and secured to the interior of the cap, the said cap being secured independently thereof to the point of the shell.

11. A projectile cap of steel having an inner lining or cap of softer metal, the two being secured together by coöperating projections and recesses and adapted to be applied to the point of a projectile.

In testimony whereof we have signed this specification in the presence of two subscribing witnesses.
